UNITED STATES PATENT OFFICE.

PETER RASAR, OF ILLIOPOLIS, ILLINOIS.

IMPROVEMENT IN NECK-YOKES.

Specification forming part of Letters Patent No. **222,839**, dated December 23, 1879; application filed October 24, 1879.

To all whom it may concern:

Be it known that I, PETER RASAR, of Iliopolis, in the county of Sangamon and State of Illinois, have invented certain new and useful Improvements in Neck-Yokes; and I do hereby declare that the following is a full, clear, and exact description of the invention, which will enable others skilled in the art to which it appertains to make and use the same, reference being had to the accompanying drawings, which form a part of this specification.

Figure 1 is a front view. Fig. 2 is a longitudinal vertical sectional view, and Fig. 3 is a cross-section taken through the center.

Corresponding parts in the several figures are denoted by like letters of reference.

This invention relates to neck-yokes; and it consists in certain improvements in the construction of the same, which will be hereinafter more fully described, and particularly pointed out in the claim.

My improved neck-yoke consists of two parts, A A, the ends of which are firmly connected by rivets B B, or in some other suitable manner. The parts or pieces A A are

spaced by suitable braces C C, plates D D being interposed to insure strength. Between the braces C C is swiveled or pivoted a ring, E, which may be covered with leather or other suitable material, F.

In operation the ring E is adjusted upon the end of the tongue, and the ends of the yoke are buckled to the collars in the usual manner.

Having thus described my invention, I claim and desire to secure by Letters Patent of the United States—

The herein-described improved neck-yoke, consisting of two parts, A A, having their ends firmly connected by means of rivets B B, and their central portions spaced by means of plates D D and braces C C, in combination with a swiveled ring, E, substantially as and for the purpose set forth.

In testimony that I claim the foregoing as my own I have hereto affixed my signature in presence of two witnesses.

PETER RASAR.
